UNITED STATES PATENT OFFICE.

FREDERIC JOHN WHINCAP, OF GRAND RAPIDS, MICHIGAN, ASSIGNOR TO KIRSCH COMPANY, OF STURGIS, MICHIGAN, A CORPORATION OF MICHIGAN.

DESIGN FOR AN END ORNAMENT FOR CURTAIN POLES.

Application filed December 17, 1928. Serial No. 29,307. Term of patent 3½ years.

To all whom it may concern:

Be it known that I, FREDERIC JOHN WHINCAP, a subject of the King of England, and a resident of Grand Rapids, county of Kent, and State of Michigan, have invented a new, original, and ornamental Design for an End Ornament for Curtain Poles, of which the following is a specification, reference be-

ing had to the accompanying drawing, forming a part hereof, which is a front perspective view of the end ornament for curtain poles showing my new design.

I claim:

The ornamental design for an end ornament for curtain poles as shown.

FREDERIC JOHN WHINCAP.
